UNITED STATES PATENT OFFICE

OSCAR R. PETERSON, OF BROOKLYN, NEW YORK

SAFETY RAZOR

Application filed January 16, 1932. Serial No. 587,062.

This invention relates to safety razors of the reciprocating type in which a blade assembly unit is caused to reciprocate by using the razor and which blade unit may be conveniently disassembled for replacement of the blade.

The main object of my invention is to provide a reciprocating safety razor with a blade unit which may be so readily taken apart that it is substantially automatic in releasing the blade for renewal.

Another object is to provide such a razor with known means for reciprocating the blade unit when the razor is brought into contact with the face of the person to be shaved.

Another object is to have a razor of the character indicated which may be used with or without the reciprocating feature at will by merely changing the position of the razor very slightly during use.

Other objects and the various advantages inherent in the novel structure embodying my invention will appear more fully in detail as this specification proceeds.

In the accompanying drawings forming part hereof,

Fig. 1 is a perspective view of a reciprocating safety razor made according to my invention and embodying all the useful and novel features thereof in a practical form.

Fig. 2 is a view of the razor in operative position for shaving with the reciprocating feature in active use.

Fig. 3 is a top plan view of the razor of Fig. 1.

Fig. 4 is a similar view to Fig. 1 wherein the blade assembly unit is more fully revealed by the raising of an upper frame or bridge whereon a roller for reciprocating the unit is carried.

Fig. 5 is a top plan view of the razor as in Fig. 4.

Fig. 6 shows the upper portion of the razor with the parts in the position of Fig. 4, but with the blade and a cap plate therefor removed from the blade assembly unit.

Fig. 7 is similar to Fig. 6, but with all parts of the blade assembly unit removed.

Fig. 8 is a side edge view of the razor fully assembled as in the first three views.

Fig. 9 is a similar view with several of the upper parts in vertical section in order to reveal their structure.

Fig. 10 shows a part of the blade assembly unit, namely the cap plate for the blade.

Fig. 11 is an end view of the same.

Fig. 12 is a top plan view of the same plate with a portion in section to disclose the extent of the slot therein.

Fig. 13 shows a latch part which normally extends into the slot just mentioned in the cap plate.

Fig. 14 is another view of said latch part.

Fig. 15 shows another part of the blade assembly unit, or the base plate therefor.

Fig. 16 is another view of the same as seen from below.

Fig. 17 is an end view of the same base plate.

Throughout the various views, the same reference numerals indicate the same or like parts.

In reciprocating razors, it is usually the case that some feature of inconvenience enters into the structure, inasmuch as the blade ordinarily is not reciprocated alone, but forms a part of an assembled unit which in movement carries the blade along with it. Such a blade unit, as it may be termed for short, is therefore assembled by means of a nut screwed on a threaded stud, or in some other more or less troublesome manner retained in assembled condition. When it is desired to replace a blade in such a razor, the structure presents an item of inconvenience which may mean loss of time and be annoying.

In the present invention, however, the blade unit does not have to be removed from the razor and yet, withal is disassembled at a touch.

Hence, in the practice of my invention, a handle 1 is secured to a frame 2 having a pair of corresponding jaws 3, 3 at one end and a series of projections 4, 4 along the edges forming guards, while immediately within said guards, the frame has opposed and corresponding dove-tail gibs 5, 5. A base plate 24

which is provided with beveled edges 27, 27 is normally in slidable position between the gibs 5, 5 upon the frame 2 and retained thereon against loss as will immediately appear.

5 The handle is preferably secured to the frame by means of a threaded projection 30 which terminates in a stud 31 normally projecting into an elongated slot 25 in the base plate 24. The latter may thus move along 10 gibs 5, 5 to a limited extent, but may not be slid off the frame until the handle is unscrewed two or three threads, whereupon it may, of course be removed. A blade 11 of known type may be laid upon the base plate 15 and the locating studs 17, 17 of the base plate will pass through the apertures common to such blades and thus properly position the blade upon the plate. Then, in order to secure the blade upon the plate, a cap plate 10 is placed upon the blade, the apertures therein similar to 33 causing the same to be accurately located with respect to both blade and base plate. Furthermore, the studs 17, 17 are each provided with undercut slots 26, 26, 25 while the cap plate has a pair of similar latching members 22, 22 provided with finger pieces 15, 15 by which to manipulate them and with inner latching edges 34 adapted to engage in said slots. In order to positively 30 cause engagement of said latching edges with said slots, each latch member is further provided with a horizontal plunger 21 extending partly into a projection 20 on the cap plate in which a spring 32 is located and against which 35 said plunger bears. The spring tends to urge the plunger 21 outward and thereby draws the latch 22 outward with its latching edge 34, and this latches the respective end of the cap plate in position on the base plate over 40 the blade and thus secures the same. Owing to the fact that the studs 17, 17 are rounded, the latching edges automatically give way against the spring pressure when the cap plate is forced down upon the studs, and 45 when the plate has been depressed to the place where the same holds the blade down on the base plate, the latching edges snap into the slots on the studs and the latches and their finger pieces suddenly project outward.

50 However, in order to provide a definite normal position for the latch member and also to retain the same against loss, a slot 35 is provided therein near the larger slot 23 through which the stud passes. In the projection 20 upon each end of cap plate 10 there is a pin 19 fitted so as to extend through said slot 35, thus limiting movement of the member to the extent of the dimensions of said slot. The cap plate has a slot 29 extending 55 inward from each end to receive the latch member 22, the pin 19, of course extending through said slot.

60 The blade unit as a whole is thus slidable longitudinally upon frame 2 of the razor, 65 being limited, as already described by the

linear dimension of slot 25 in the base plate. For the purpose of automatically reciprocating the blade unit, the cap plate has a projection 13 located upon a flat portion 14, 70 while above the unit is normally located a cam roller 8 having a cam slot 9 engaging the projection 13. The roller is preferably knurled to provide friction against the face 36 of the person shaving, which will cause the roller to rotate upon drawing the razor downward upon the face. In order to rotatably support the roller, a bridge indicated generally by 6 is hinged at the end of frame 2 generally indicated at 18 and has a pair of lugs 16, 16 through which is inserted the pin 28 to serve as a pivot or shaft for said roller. The free end of the bridge has a pair of corresponding finger pieces 7, 7 upon whose outer edges a pair of notches 12, 12 are formed, the same being designed to engage the jaws 3, 3 of the frame. The finger pieces are somewhat resilient as they form a bifurcated end of the bridge, and when the same are slightly pressed together, they will be disengaged from the jaws of the frame because notches 12, 12 will be freed. When the bridge has been open and is swung downward, the finger pieces will enter between the jaws and then snap into locked position, due to the fact that the notches will suddenly engage the jaws. On the other hand, the finger pieces are so formed exteriorly that when the fingers are pressed upon their outer edges, the notches tend to release suddenly and the finger pieces to instantly slip upward out of the fingers, which action is effective to swing the bridge upward into the position shown in Fig. 4. In this position, the blade assembly is accessible, and if the fingers are caused to press inward upon both finger pieces 15, 15 of the latch members of the cap plate, said latch members will release the plate from the unit, as the blade will tend to straighten and will therefore raise the cap plate to a certain extent. Both the cap plate and the blade may then be lifted off without further ado, when solely the base plate will remain in position upon the frame as seen in Fig. 6.

110 When a new blade is placed in position, and the cap plate again laid upon the base plate over the new blade, it is but necessary to press down the cap plate, when the latches will snap into engagement with the slots of the base plate studs, and the unit will be assembled. The bridge may then be swung down again until its finger pieces engage their notches with the frame jaws, and the bridge is locked while the roller has again 115 engaged the projection on the cap plate. As the cam slot is diagonal, rotation of the roller will force the blade unit to move first in one direction and then in the opposite direction, and so on.

Variations may be resorted to and parts may be used without others.

Having now fully described my invention, I claim:

5. 1. A safety razor including the combination, with a handle, of a frame having guards thereon and a pair of opposite gibs, a blade assembly unit having a plate fitting between said gibs and slidable along the same, a bridge 70 overlying said assembly which is removably attached to said frame and which has means mounted thereon for reciprocating said blade assembly, and a projection upon said handle extending up into said plate in order to limit 75 movement thereof and retain the same and said unit against loss when said bridge is removed, there being a slot in said plate forming a limited clearance for said handle projection.
10. 2. A safety razor including the combination, with a handle, of a guard frame upon said handle having retaining gibs thereon, a base plate slidably mounted between said gibs on said frame, a cap plate adapted to be 80 located upon said base plate and retain a blade thereon, studs upon one plate extending into the other plate, there being slots in said studs, releasable latch members upon the latter plate adapted to engage said slots in 85 said studs, whereby to secure said plates and the inserted blade in an assembled unit, and means for reciprocating said blade assembly unit, that is said plates and said blade.
15. 3. A safety razor including the combination, with a handle, of a guard frame upon 90 said handle having a pair of retaining gibs thereon, a base plate slidably mounted between said gibs on said frame, there being a slot in said plate, a threaded projection upon 95 said handle screwed into said frame and terminating in a portion extending into the slot in said plate in order to provide for a limited movement of said plate and retain the same against loss, and means for attaching a blade 100 to said base plate including a removable cap plate.
20. 4. A safety razor including the combination, with a handle, of a guard frame attached to said handle having retaining gibs 105 thereon, a plate slidably retained between said gibs upon said frame, means upon said handle limiting movement of said plate and preventing removal of the same from said frame, a second plate detachably secured to 110 said first plate in order to releasably retain a blade thereon, a shiftable support upon said frame, means upon said support for reciprocating said plate, and means upon said plate engageable by said means upon the support.
25. 5. A safety razor including the combination, with a handle, of a guard frame mounted upon said handle, a base plate movably supported upon said guard frame, locating 115 studs fixed upon said plate, there being slots in said studs, a second plate adapted to be 120
- placed upon said base plate in order to retain a blade thereon and adapted to be properly located on said base plate by engaging said studs, latch members associated with said second plate and extending into the same and furthermore, engageable with said slots in order to retain the second plate assembled upon said base plate, finger pieces upon said latch members whereby to disengage the same from the slots in said studs, and springs urging said latch members into engagement with said slots, there being means to reciprocate said plates and the blade held thereby.
6. A safety razor comprising a guard frame mounted on a handle, a blade base plate slidably mounted on said guard frame, a blade, a blade cap plate, releasable means for securing said blade cap plate to said base plate, a bridge overlying said blade cap plate and detachably secured to an end of said guard frame, said blade base plate, blade and blade cap plate comprising a blade assembly 130 slidable as a unit between said guard frame and said bridge and cooperative means mounted on said bridge and blade assembly whereby said blade assembly is reciprocable with respect to said guard frame and bridge and therebetween for the movement of the cutting edge of said blade overlying said guard.
- In testimony whereof, I have signed my name to this specification.
- OSCAR R. PETERSON.
